UNITED STATES PATENT OFFICE.

JACOB J. POMERANZ, OF BROOKLYN, NEW YORK.

DESIGN FOR A NOSE BRIDGE FOR EYEGLASSES.

Application filed May 11, 1928. Serial No. 26,639. Term of patent 14 years.

To all whom it may concern:

Be it known that I, JACOB J. POMERANZ, a citizen of the United States, residing at Brooklyn, in the county of Kings and State of New York, have invented a new, original, and ornamental Design for Nose Bridges for Eyeglasses, of which the following is a specification, reference being had to the accompanying drawings, forming part hereof.

In said drawings, Fig. 1 is a front elevation or face view of the nose-bridge as mount-

ed to the lens-rims of eye-glasses, the latter being shown in dotted outline; Fig. 2 is a top edge view of the same; and Fig. 3 is a vertical section through the nose-bridge; said views showing my new design.

I claim:

The ornamental design for nose-bridge for eyeglasses as shown.

Dated May 2nd, 1928.

JACOB J. POMERANZ.
